UNITED STATES PATENT OFFICE.

JAMES A. CAMERON AND GUSTAF BIRGER BIRCH, OF BROOKLYN, NEW YORK, ASSIGNEES
TO CAMERON MACHINE COMPANY, OF BROOKLYN, NEW YORK, A CORPORATION OF
NEW YORK.

PROCESS FOR MAKING SURGICAL BANDAGES.

1,256,657.

Specification of Letters Patent. Patented Feb. 19, 1918.

Original application filed October 10, 1914, Serial No. 866,012. Divided and this application filed March 3, 1916. Serial No. 81,809.

To all whom it may concern:

Be it known that we, JAMES A. CAMERON and GUSTAF B. BIRCH, both citizens of the United States, and residents of the borough 5 of Brooklyn, in the county of Kings, city and State of New York, have invented certain new and useful Improvements in Processes for Making Surgical Bandages, of which the following is a specification.

10 This invention relates to the art of making surgical bandages.

The main object of this invention is to reduce the number of operations necessary to produce bandages and to obtain as wide a 15 bandage as possible from a given width of web.

In carrying out this invention we employ a process which consists in slitting a web of material lengthwise by severing it with 20 an undulating cut so as to simultaneously destroy the continuity of the warp threads adjacent to the cut and so as to leave a scalloped edge formed by weft threads of unequal length after which the material is 25 wound into coils or rolls, preferably on a single shaft which when removed enables the operator to separate the rolls and thereby produce a plurality of finished bandages. The product thus formed is produced by a 30 much smaller number of operations and is of such a character that the edges thereof will not unravel since the outermost threads as described before are destroyed in the process of slitting the fabric and the remaining 35 warp threads are held in place by the scalloped edge formed by the weft threads of unequal length.

Preferably the severed warp threads may be removed from the bandage before it is 40 rewound, by any suitable means, such as means for causing a blast of air to impinge upon the undulating edges.

In carrying out this process a machine is utilized which is provided with a slitting 45 means located in the path of the moving web for slitting the web lengthwise before winding on undulating lines of severance, thereby acting on the warp and weft threads in the manner described. The slitting means

preferably embrace a backing member of 50 suitable character and a rotary cutting member having a tortuous cutting edge.

The machine here disclosed is claimed in the pending application of the applicants herein filed August 3, 1915, Ser. No. 43,370. 55

In the accompanying drawings the invention is disclosed in a concrete and preferred form from which, however, departure may be made without departing from the scope of the invention as expressed in the appended 60 claims.

In the said drawings Figure 1 is a vertical sectional view through a machine which may be utilized in carrying out the process.

Fig. 2 is a general plan view of the device 65 on the line 2-2 of Fig. 1 partly in section and partly broken away for clearness of illustration.

Fig. 3 is an edge view of a portion of the tortuous rotary cutter. 70

Fig. 4 is a view of a portion of the web showing the undulating line of severance with respect to the warp and weft threads.

Fig. 5 is a figure showing the effect of the undulating cut with the severed warp 75 threads remaining in place and with the scalloped edge formed by the weft threads of unequal length.

Fig. 6 is a view similar to Fig. 5 with the severed warp threads removed. 80

Similar characters of reference designate corresponding parts in the different views.

In the drawings 1 indicates a roll of material from which the bandages are to be made suitably supported on a core in the 85 machine, and 2 is the web member which is led therefrom over suitable guide rollers 3, 4 and 5.

At 6 is shown the rewinding mechanism of a well-known form which consists in this 90 instance of two surface rewinding rolls 7 and 8 rotating in the same direction, and a pressure roll 9 mounted to rise as the diameter of the rewound roll increases. At 11 is shown the rewinding shaft which is placed 95 between the rollers 7, 8 and 9 and on which the finished sections are rewound. The cutting device here consists of the rotary cut-

ting member 12 which is provided with a tortuous cutting edge, as is best shown in Fig. 3. There may be a number of these rotary cutting members and they are preferably mounted in brackets 13 hung on the rails 14 in a well-known manner, which rails are adapted to be raised or lowered so as to bring the cutting member 12 into engagement with the roll 8 by means of the cam 15 in a manner well-understood in the art. The cam 15 also actuates the lever 16 pivoted at 17 and provided with a tension roll 18 which serves to bring the web of material into engagement with the rolls 7 or 8, or both. 15 In the present embodiment of the invention one of the rewinding rolls 8 constitutes the backing member for the cutting member 12. This backing member is preferably provided with an inner core 19 and a plurality 20 of outer shells 20 of a material harder than the material of which the rotary cutting member 12 is made, so that the cutting member will not cause indentations in the backing roll. The tortuous cutting edge of the 25 rotary cutting member 12 is preferably blunt, that is to say, it is not a sharp cutting edge since, if it were, it would be destroyed by coming in contact with the hard outer shells 20 of the backing member. The 30 web of material is led over the guide rolls 3, 4 and 5 and over the tension roll 18 and in between the backing roll 8, and the rotary cutting member 12, which by its action, slits the web longitudinally on undulating lines, 35 as is indicated at 27 in Fig. 4. It will be noted that this undulating cut will sever a number of the warp threads 28 within the confines of the lateral limits of the undulating cut, the effect of which may be clearly 40 seen in Fig. 5. At the same time the undulating cut will sever the weft threads 29 in such a manner as to leave a scalloped edge formed by weft threads of unequal length recurring at like intervals, as is shown in 45 Figs. 5 and 6. After having been acted upon by the cutting member the material passes around the roller 8 and thence to the rewinding shaft 11 which rewinds the slit and finished sections side by side into a plurality 50 of coils or rolls. The scalloped edges of the finished bandage rolls, into which the material has been rewound, preserve the same interlocked relation that the sections possessed when they left the cutting member with a 55 consequent freedom from overlapping. The finished rolls are accordingly easily separated from each other without injury to the material. When a sufficient diameter of material has been rewound the shaft 11 is removed from the machine and the rolls of finished bandage are removed therefrom. 60

If desired, the web may be led over a hollow guide roller 21, which is interposed

in the line of travel between the slitting means and the rewinding means and which 65 is open to the atmosphere, as shown at 22. From thence the web may pass back to the upper portion of the roller 8 and then to the rewinding shaft 11. The hollow guide roller 21 is in connection, by means of suitable piping at 23, with the containers or tanks 24, and an air nozzle 25 of suitable construction is arranged adjacent the slot 22 of the hollow guide roller 21 so that as the web travels over the said guide roller 70 21 air blown through the nozzle will carry the severed warp threads into the tanks 24. These tanks may be provided with suitable screening means for retaining the particles of the warp threads and for permitting the 80 escape of the air in a well-known manner.

The rewinding shaft 11 is adapted to slidably engage the guiding members 10 so as to be free to rise as the diameter of the re-wound material increases. 85

A bracket shown at 26 is adapted to support a rewinding shaft 11 while an exchange of shafts is being made due to the filling of one of the shafts.

What is claimed is:

1. The process of making surgeon's bandages which consists in slitting a moving web of material lengthwise by severing it with an undulating cut so as to simultaneously destroy the continuity of warp threads adjacent to the cut and so as to leave a scalloped edge formed by weft threads of unequal length, and then removing the severed warp threads from the moving web. 90
2. The process of making surgeon's bandages which consists in feeding a web of material, slitting the web lengthwise by severing it with an undulating cut while feeding the same so as to simultaneously destroy the continuity of warp threads adjacent to the cut and so as to leave a scalloped edge formed by weft threads of unequal length, then removing the severed warp threads, and then rewinding the slit sections. 100
3. The process of making surgeon's bandages which consists in feeding a web of material, slitting the web lengthwise with an undulating cut so as to form sections with contiguous scalloped edges, then removing the severed warp threads, and finally re-winding the sections with the contiguous scalloped edges in interlocked but not in overlapped relation. 110
4. The process of slitting and rewinding sheet material which consists in first slitting a web of material with an undulating cut so as to form sections with contiguous scalloped edges, and then rewinding the sections with the contiguous scalloped edges in interlocked but not in overlapped relation. 120
5. The process of slitting and rewinding

sheet material which consists in first slitting a web of material with an undulating cut so as to form sections with contiguous scalloped edges, and then rewinding the sections on the same shaft without overlapping the scalloped edges.

Signed at New York city, in the county of

Kings and State of New York, this 1st day of March, A. D. 1916.

JAMES A. CAMERON.
